UNITED STATES PATENT OFFICE.

WARD S. IRELAND, OF OWENSBORO, KENTUCKY.

TYPE-WRITING MACHINE.

1,098,113.

Specification of Letters-Patent. Patented May 26, 1914.

Application filed March 11, 1913. Serial No. 753,630.

To all whom it may concern:

Be it known that I, WARD S. IRELAND, a citizen of the United States, and a resident of Owensboro, in the county of Daviess and State of Kentucky, have invented certain new and useful Improvements in Type-Writing Machines; and I do hereby declare the following to be a full, clear, and exact description of the invention, such as will enable others skilled in the art to which it appertains to make and use the same.

This invention relates to improvements in typewriting machines and more particularly to paper feeding mechanism therefor,—the object of the invention being to provide a simple and efficient paper feeding mechanism which shall be especially adaptable for use with stenographic writing machines in which the paper is fed forward with each manipulation of a key or of several keys simultaneously.

With this object in view, the invention consists in certain novel features of construction and combinations of parts as hereinafter set forth and pointed out in the claims.

In the accompanying drawings, Figure 1 is a longitudinal sectional view of a stenographic typewriting machine embodying my improvements. Fig. 2 is a view in perspective showing the paper feeding mechanism. Fig. 3 is a view partly in section showing the paper engaging fingers and wheels or disks with which they coöperate, and Fig. 4 is a sectional view on the line $y-y$ of Fig. 3.

1 represents the frame of the machine, wherein is pivotally mounted a plurality of key levers 2 provided respectively with keys or buttons 3 and with upwardly projecting arms 4. A notched bar 5 is disposed transversely in the upper portion of the framework intermediate the ends thereof and in this notched bar a plurality of type levers 6 are pivotally supported between their ends and each provided at its upper end with a type 7,—the lower ends of said type levers being pivotally connected with the upper ends of the key lever arms 4.

Bars 8 are located on the frame 1 at respective sides thereof and to the forward ends of these bars, links 9 are hinged and supported by the framework. The forward ends of these links are provided with elongated slots 10 for the reception of screws 11 which adjustably connect a transverse platen bar 12 between said links,—said

platen bar being thus disposed transversely over the central portion of the framework and directly in line with the type 7. The platen bar is preferably provided with a yielding strip or platen 13. It will be apparent that by mounting the platen bar adjustably as above explained, the yielding platen face or strip can be adjusted toward and from the engaging faces of the type. 60

A shaft 14 (mounted in the bars 8) extends from one of said bars 8 to the other and upon this shaft, a plurality of wheels or disks 15, 16, 17, are mounted. Levers 18 are mounted between their ends on the shaft 14 in proximity to the bars 8 and the upper ends of these levers are provided with pins 19 on which spring actuated sleeves 20 are mounted and each of these sleeves is provided with an engaging finger 21 which co-operates with the wheels or disks 15—17 to feed the paper as presently explained. A yoke 22 is secured at its ends to the bars 8 of the framework and the intermediate portion of this yoke is provided with lugs 23 which support a pin 24 for the accommodation of a spring actuated sleeve 25 carrying a finger 26 to coöperate with the intermediate wheel or disk 16 for preventing retrograde movement of the paper. The yoke 22 is also provided with a serrated or toothed edge 27 to facilitate the ready severance of the paper strip. 70

Standards 28 rise from the platen bar 12 and between these standards, guide rolls 29—30 are mounted. A guide 31 is disposed below the platen bar and may be in the form of an integral flange depending from the lower edge of the platen bar 12. A door 33 is provided for the rear end of the frame or casing of the machine and this door carries a bracket 34 in which a roll of paper 35 is mounted. The paper strip 36 extends from this roll under the guide 31; then upwardly and around the roll 30 and 95 upper guide roll 29. After passing over the roll 29 the paper strip is made to pass downwardly and around the roll 30 and from the latter, the strip passes rearwardly over the wheels or disks 15, 16, 17, and under the fingers 21 and 26. A guide plate 32 is provided for assisting in the threading of the paper past the roller 30. 100

A universal bar 37 is supported by links 38 pivotally attached at their upper ends to the notched bar 5,—said universal bar being located in front of the upper portions of the 110

key lever arms 4 and preferably provided with a cushion 39 to be engaged by said key lever arms. The links 38 are made in the form of arms rising from bars 40 which project rearwardly from the ends of the universal bar and to the rear ends of said bars 40 links 41 are pivotally attached, the rear ends of said links being pivoted to the lower arms of the levers 18. The bars 40 and arms or links 38 are connected with the upper portion of the framework by means of one or more springs 42 which serve to normally retain and to return the parts.

Suitable inking mechanism is provided but as this constitutes no part of the invention described and claimed herein, a detailed description of the same will be superfluous, but suffice it to say that the ribbon 43 is caused to pass between the type and the paper strip.

It will be observed that the paper strip is bowed or loose between the guides 31 and 29 and also between the guides 29 and 30 and that when a key lever is operated, the type 25 will be caused to imprint on this loose or bowed section of the paper strip. It will also be observed that when a key lever is operated, the engagement of its arm 4 with the universal bar 37 will cause motion to be transmitted through the arms 40 and links 41 to the levers 18. Said levers will thus be caused to rock and to move the fingers 21 and, said fingers being in engagement with the paper strip passing over the wheels or disks 15 and 17, will cause said paper strip to be moved forwardly a distance sufficient to receive another line of writing. When the paper strip is thus moved, retrograde movement thereof will be prevented by the finger 26 in coöperation with the wheel or disk 16. When the key lever shall have been released, it will be returned to its normal position by the action of a spring 44 and the remaining parts of the mechanism will be returned to their normal positions by the operation of spring 42.

The connecting devices between the universal bar and the paper feed devices, should be such that the completion of a feeding movement of the paper and the engagement of a type with the paper will be practically simultaneous, and for this reason, the universal bar is provided with a finger 45 which, in coöperation with a pad 46, constitutes a yielding stop for said universal bar and the parts which it controls. As paper feeding fingers and type bars are both moved simultaneously by the universal bar, the fingers will feed paper as long as a type bar moves. If the type bar moves after gripping to the platen, on account of pliability of platen face, the fingers will be feeding paper forward after the type has caught the paper and held it; hence there must be some slack in the paper between type and fingers

for the fingers to feed to prevent their catching the paper and tearing it. By arranging the guides for the paper in front of and above the platen, in the manner hereinbefore described, and clearly shown in Fig. 1 of the drawing sufficient distance between the guides and the platen will be provided to enable the resiliency of the paper to produce, the slack in the paper, which can be taken up by the feeding fingers after the type strike.

Having fully described my invention what I claim as new and desire to secure by Letters-Patent, is:

1. In a paper feeding mechanism for typewriting machines, the combination with a frame, of a plurality of disks or wheels, a plurality of pivoted levers, spring pressed fingers carried by said levers and adapted to coöperate with said disks or wheels, a plurality of key bars, a universal bar operable by the key bars or levers, and connections between said universal bar and the first mentioned levers.

2. In a paper feeding mechanism for typewriting machines, the combination with a frame, of a plurality of wheels or disks, levers mounted on the frame, spring pressed fingers carried by said levers and coöperating with certain of said wheels or disks to feed a paper sheet, a spring pressed finger carried by a fixed support and coöperating with another of said wheels or disks to prevent retrograde movement of the paper sheet, key levers, a universal bar, and connections between the universal bar and the first mentioned levers.

3. In a typewriting machine, the combination of printing means, paper feeding means, means below the printing means for loosely supporting a supply of paper, paper guiding means between the printing point and the paper feeding means, said paper guiding means having such relation to the printing means as to cause the resiliency of the paper to slacken the latter above and past the printing means when the type of the latter recede.

4. In a typewriting machine, the combination with printing means, paper feeding means, means below the printing means for loosely supporting a supply of paper, paper guiding means comprising a plurality of guides having such relation to the printing means and to each other that the resiliency of the paper will cause the latter to slacken above and past the printing means when the type of the latter recede.

5. In a typewriting machine, the combination with printing means and paper feeding means, of a plurality of paper guiding devices located between the printing means and the feeding means and located in different horizontal planes above the printing plane of the printing means, said guiding

devices being located with respect to the printing plane of the printing means so that the resiliency of the paper will render the same slack above and past the printing plane 5 of the printing means when the type of the printing means recede.

6. In a type writing machine, the combination with printing means, paper feeding means and means below the plane of the 10 printing means for supporting a paper supply roll, of paper guiding devices above and below the printing plane of the printing means, said paper guiding devices being

positioned with respect to the printing means so that the resiliency of the paper 15 will render the latter stack in front of and above the printing plane of the printing means when the type of the printing means recede.

In testimony whereof I have signed this 20 specification in the presence of two subscribing witnesses.

WARD S. IRELAND.
